US0D1057644S

(12) **United States Design Patent** (10) **Patent No.:** **US D1,057,644 S**
(45) **Date of Patent:** **** Jan. 14, 2025**

(54) **BATTERY PACK**

(71) Applicant: **Einride AB**, Stockholm (SE)

(72) Inventor: **Dawid Dawod**, Stockholm (SE)

(73) Assignee: **Einride AB** (SE)

(**) Term: **15 Years**

(21) Appl. No.: **29/859,970**

(22) Filed: **Nov. 15, 2022**

(30) **Foreign Application Priority Data**

May 17, 2022 (EM) 009027816-0001

(51) **LOC (15) Cl.** **13-02**

(52) **U.S. Cl.**

USPC **D13/103**

(58) **Field of Classification Search**

USPC D13/103, 104, 106, 108, 107, 110, 112, D13/118, 119; D14/203.1

CPC F21L 4/085; H02J 7/0044; H02J 7/0045; H02J 7/0013; H02J 7/0019; H02J 7/0042; H01M 10/46

See application file for complete search history.
